CLAIM

The ornamental design for a cabinet incline for workplace as shown and described.

DESCRIPTION

FIG. 1 is a front perspective view of the cabinet incline for workplace showing my new design, shown in condition of use;

FIG. 2 is a front elevation view thereof;

FIG. 3 is a rear elevation view thereof;

FIG. 4 is a side elevation view thereof;

FIG. 5 is the other side elevation view thereof;

FIG. 6 is a top plan view thereof;

FIG. 7 is an exploded view thereof;

FIG. 8 is a perspective view of the cabinet incline for workplace;

FIG. 9 is a front elevation view thereof;

FIG. 10 is a rear elevation view thereof;

FIG. 11 is a side elevation view thereof;

FIG. 12 is the other side elevation view thereof;

FIG. 13 is a top plan view thereof; and,

FIG. 14 is a bottom plan view thereof.

The broken lines shown in the figures are included for the purpose of illustrating portions of the cabinet incline for workplace which form no part of the claimed design. The additional broken lines showing a cabinet in FIGS. 1 through 7 are to show environment and are not part of the claimed design.

1 Claim, 12 Drawing Sheets
